UNITED STATES PATENT OFFICE.

LYMAN R. BLAKE, OF QUINCY, MASSACHUSETTS.

IMPROVED STITCH FOR SOLES AND VAMPS.

Specification forming part of Letters Patent No. 44,275, dated September 20, 1864.

To all whom it may concern:

Be it known that I, LYMAN R. BLAKE, of Quincy, in the county of Norfolk and State of Massachusetts, have invented an Improved Stitch for Uniting Soles and Vamps, &c.; and I do hereby declare that the following, taken in connection with the drawing which accompanies and forms part of this specification, is a description of my invention sufficient to enable those skilled in the art to practice it.

This improvement relates principally to the manufacture of boots and shoes, having reference to the manner of connecting or uniting the vamps and soles. It is, however, applicable to other manufactures of leather where two parts are generally united by sewing, nailing, or pegging them together.

The invention consists in the employment of a novel stitch for uniting the pieces of leather or similar material, such stitches being formed from a continuous thread suitably prepared with wax or other adhesive substance to impart the proper degree of tenacity or adhesion in and to the parts united.

The drawing shows a sectional view of two pieces of leather joined by my improved stitch, such section showing the disposition of the thread.

To apply the stitch by hand, the pieces to be sewed are suitably fastened by clamps, nails, or otherwise, and awl-holes made at such distances apart as it is desirable to have the stitches. The thread being then laid over the holes, it may be driven successively into the series of holes from the surface *a a*, or a hook or crochet-needle may be passed through the leather from the surface *b b*, hooking into and drawing the thread successively through the series of holes.

In practicing the invention by machine the common wax-thread chain-stitch machine employing a crochet-needle may be used, a suitable device being applied to slip the stitch out of the hook when it rises from the work, so that when the work is fed and the needle descends it shall not go through the previously-formed loop, but shall descend in rear of the same. With an eye-pointed-needle machine sewing with a chain-stitch it is only necessary to detain the loop below the work when the needle rises, without so laying such loop that the needle in its next descent shall pass through

it. With the rotating-horn sewing-machine shoes can be sewed by this invention with the same facility as with the common stitch. In all of these methods of applying the stitch the closing of the work upon the thread and the adhesiveness of the wax cause the threads of each stitch to bind in the awl or needle hole. The upper portion of the stitch may be laid in a channel, and the thread may be left up some distance beyond the surface of the groove or channel for this purpose, as seen at *c*, this thread being subsequently pressed down into the channel and covered by the flap.

In performing sewing by automatic mechanism producing this novel stitch or looping it will be found convenient and expedient to draw the loops in the first place some distance above the surface of the leather in order conveniently to detach them from the hook if a crochet-needle be employed. This protruding portion of each loop is drawn back to or nearly to said surface when the next loop is made, and to regulate this withdrawal so as to prevent the loops from being withdrawn into the stock or entirely out of it, an automatic device is attached to the sewing-machine, which enters the loop, and upon which the tension of the thread is received, and upon withdrawal of this device the small loop seen at *c* is left projecting. The thread at *c* is flattened and enlarged by being tightened upon the said detaining device, and when it is pressed or hammered down into the channel formed for its reception the loops have a head which increase their holding force. Where the bight of each loop is to be drawn flush with or slightly below the surface, the device employed to prevent too great withdrawal of the loop acts to bind or clamp the thread temporarily, and the feeding device or point shown in the McKay & Mathies rotating-horn sewing-machine may be so timed and operated as to add this detaining operation to its function.

I claim—

The employment of the new stitch for uniting soles and vamps of boots and shoes, and for a similar use in other manufactures, in the manner substantially as described.

LYMAN R. BLAKE.
